WRENCH

Robert Chester Weishampel, Paterson, N. J.

Application April 13, 1936, Serial No. 74,001

6 Claims. (Cl. 81—87)

This invention relates to wrenches of the type that may be referred to as a bolt wrench intended to cooperate with the head of a bolt or with the nut thereon, usually hexagonal in form, 5 although the features hereof are applicable to bolt parts in square or other form, or analogous uses.

An object of the invention is to afford a simple, compact and efficient wrench for the uses referred to, and more especially one which has the advantages of a socket wrench and yet may be adaptable to a range of sizes, as from $\frac{7}{16}$ to $\frac{3}{4}$ inch or from $\frac{1}{4}$ to $\frac{1}{2}$ inch. The disclosed wrench is of the type having two handles, like those of a 15 pliers, which are drawn together to cause the bolt gripping jaws to approach, and it is an object to provide a wrench comprising mechanism such as to afford a quick closing movement and a firm grip upon the bolt head or nut and yet the 20 easy ability to loosen the grip for the feeding of the wrench around from one to another position in the operation of turning the bolt or nut. By the present invention these advantages are attained without the need of screw adjustments or 25 springs. Other and further objects and advantages of the invention will be pointed out in the hereinafter following description of one or more embodiments thereof.

To the attainment of such objects and advantages the invention consists in the novel wrench and the novel features of combination, arrangement and structure herein illustrated or described.

In the accompanying drawing Figure 1 shows 35 in top or face view a wrench embodying the present invention with the parts set in wide open position, the left or jaw end being considered the outer end of the wrench; and Fig. 1a is a partial view similar to Fig. 1, showing a modification of 40 structure.

Fig. 2 is a view similar to Fig. 1 but showing the wrench closed upon a nut.

Fig. 3 is a side elevation of the closed wrench.

Figs. 4, 5 and 6 are detached views of the three 45 main elements or members of the wrench.

Fig. 7 is a partial top or face view of a modified structure.

The wrench comprises principally three relatively movable members; and these may be designated as a first handle member or body A, a slide member or block B and a second handle member or swinging lever C, with a pivot pin connecting all three members.

The first handle A and the slide B are each 55 formed with a longitudinal, and preferably in-

clined, slot engaged by the pivot pin extending from the second handle C. The three members thereby are interconnected but mutually relatively longitudinally slideable, the second handle at the same time being swingable about its pivot 5 or pin relatively to the first handle and slide. The slide B carrying the inner jaw is moved outward toward the other jaw by two cooperating means as follows. The two handle members A and C are provided with a cam or analogous device between them, such that the swinging approach of the handles causes an outward thrust of the second handle member relatively to the first; this of course moving the pivot pin outwardly. Also, the second handle member C and 10 the slide B are provided with an intermediate cam or device such that said swinging movement of the second handle causes an outward thrust of the slide relatively to the pivot pin and second handle. With this double acting closing movement the approach of the handles causes the approach of the jaws and the forcible gripping of 15 the bolt head or nut between the jaws. The cams or devices are such as to afford a quick closing movement becoming more powerful as the 20 nut is gripped.

Describing next the separate members, the body or lower handle member A has its handle extension A' at its inner or right end, and at its outer end it carries the first or outer jaw A², 30 shown as an upstanding projection formed two-sided to engage two sides of a hexagon bolt part D. The shank part A³ has a hole A⁴ formed near the jaw ample in size to accommodate freely a bolt extending beyond the nut to be operated by 35 the wrench. Also the shank has a slot A⁵ in which the fulcrum pin C² may play, and this slot may be somewhat slanted so that the fulcrum shifts laterally when moved longitudinally. Between the slot and handle the member A has a 40 cam A⁶ shown as a shoulder curved to cooperate with a complementary cam C³ on the second handle member or lever.

The slide or block B has flanges B' fitting it to shift longitudinally along the shank A³ without swinging, and it carries the inner jaw B² upstanding from the slide and facing the outer jaw A², so that the outward sliding of block B closes the jaws. The slide B has a slot B³ accommodating the pivot pin and this may be slanted oppositely 45 to slot A⁵ of member A. The slide B may retract substantially into contact with cam A⁶ when the wrench is wide open, as seen in Fig. 1, and its near inner corner B⁴ is rounded away to admit the cam C³ to be described between the slide and 50 55

cam A⁶. The slide near its outer end may have a cam surface B⁵ to cooperate with a cam C⁴ on the member C. The cam B⁵ may be the inner side of the projection constituting the jaw B².

5 The second handle member C is the jaw operating lever of the wrench, its handle end C' being pulled toward handle A' to grip the bolt. The member C has the pin or stud C² forming a pivot or fulcrum, and this may be attached rigidly on 10 the member, projecting through the slots A⁵ and B³ and there headed, as over a washer, or it may be a pin inserted in a hole in member C and riveted or otherwise enlarged at both ends.

The second handle or lever C has a cam or 15 shoulder C³ cooperating with cam A⁶. These two cams constitute an intermediate device such that the swinging together of the handles causes outward thrust of the second handle relatively to the first. The cam C³ enters between slide B and 20 cam A⁶ and its motion forces the pivot C² to move outwardly, toward the jaws.

The second handle has also a cam or surface C⁴ 25 cooperating with the cam B⁵ of the slide B. These constitute an intermediate device such that the swing of handle C toward handle A causes the cam C⁴ to thrust outwardly the slide and its jaw.

Both of the described thrusts afford powerful 30 grip, due to the character of the cams, and the two cooperate to afford a quick closing of the jaws upon the bolt head or nut D, the power increasing as the bolt is engaged and gripped. By then squeezing together the handles and swinging the wrench bodily the bolt head or nut is turned as 35 desired. By slackening the handle pressure the wrench is readily fed or swung idly around to the extent of 60° or 120° to take a grip at a new position on the bolt. Both the idle and the active movements are conveniently and quickly performed without danger of marring or burring the bolt head or nut. The extent of each feed movement will depend on the shape of the nut. With a square nut it may shift 90° at each movement; with a hexagon 60° or 120°; with an octagon 40 45°, 90° etc.

The upstanding projections or jaws A², B² when active constitute in effect a socket, and the wrench is operable as a socket wrench, engaging four faces on the nut. These jaws project from members A and B at right angles to the plane of swing of the handles. The hole A⁴ between the jaws allows engagement over a bolt shank as with a flat wrench, but a ledge A⁸ of metal between the hole and jaw is provided.

55 The wrench may be supplemented to afford a monkey wrench engagement with a nut, as by extension lugs or jaws A⁷ and B⁷ on the members A and B respectively as indicated in Fig. 1a. No screw is necessary for adjustment as the wrench 60 readily takes care of a range of sizes, as 1/4 to 1/2 inch or 3/4 to 1 inch; and for convenience a series of the wrenches hereof may be kept at hand each for a different range of sizes.

The wedging or thrusting device consisting of 65 the cooperating cams A⁶, C³ or B⁵, C⁴ may be replaced by an equivalent device affording a similar thrust. For example as shown in Fig. 7 a short link C⁶ is arranged between members A and C at such slant that as the handles are drawn together the member C and pivot C² are thrust outwardly by toggle action. Part of the handle C and the link C⁶ indeed constitute a toggle, the action of which in being straightened is a 70 first quick movement of closing the jaws toward the nut, and then a powerful pressure. As al-

ready stated the cam-pairs A⁶, C³ and B⁵, C⁴ are of such curvatures, for example as shown, as to afford the quick first movement and the powerful grip.

The slant of the slots A⁵, B³ has the effect of 5 causing the pivot pin and second handle to shift sideways when closing the wrench, thus modifying the actions of the cam pairs, and permitting increased gripping pressure. However, the slots might be curved to determine any desired 10 action, or longitudinally straight, with proper redesign of the cam pairs. Fig. 7 shows straight slots in members A and B.

In all embodiments the double action or compound motion takes place, as may be redescribed 15 as follows. When handle C is swung closed the device A⁶, C³ or C⁶ acts to thrust member A relatively inward, or to the right in the drawing. The same motion at the same time thrusts member B outward, to the left. By thus pushing apart 20 in opposite directions the handle swing forces toward each other the two jaws A² and B².

Another feature should be mentioned, namely 25 that the base wall of the shank A³ of the first handle member provides a narrow ledge A⁸ between the hole A⁴ and the jaw A². The hole A⁴ may be of pear shape since with a smaller nut the bolt will be smaller and closer to the jaw A², the small end of the pear shape hole accommodating the smaller bolts. Even with the smallest bolts 30 however the ledge A⁸ serves the purpose of resting upon the bolt during the operation of the wrench, so that the wrench will not drop off the nut or out of position. The wrench will usually be used in a position inverted as compared to 35 Fig. 3 and as the wrench works the nut and is ratcheted back for each new grip, the ledge A⁸ prevents it from slipping off and holds it in proper relation to the nut being turned.

There has thus been described a wrench available 40 for bolt heads or nuts which embodies the principles of the present invention and attains the described advantages. Since many matters of combination, arrangement and structure may be variously modified without departing from the 45 principles of the invention it is not intended to limit the invention to such matters except to the extent set forth in the appended claims.

I claim:

1. A bolt wrench having a first handle member 50 carrying an outer jaw and a slide member slidable endwise on the first handle member and carrying an inner jaw and a second handle member swingable relatively to the first to close and open the wrench; and characterized as follows: the second 55 handle member having a pivot pin engaging longitudinal slots in the first handle and slide members thereby connecting the three members while permitting longitudinal movements of each relatively to the others and swinging of the second 60 handle member, the two handle members having between them an intermediate device causing outward endwise thrust of the second handle member accompanying its swinging approach to the first, and the second handle member and slide 65 having between them an intermediate device causing outward thrust of the slide accompanying the swinging approach of the second handle member, whereby swingingly closing the two handle members causes the jaws to close upon the bolt 70 head or nut.

2. A wrench as in claim 1 and wherein the first intermediate thrusting device consists of 75 co-operating cam shoulders on the two members affording a wedging action.

3. A wrench as in claim 1 and wherein the second intermediate thrusting device consists of cooperating cam shoulders on the two members affording a wedging action.
- 5 4. A wrench as in claim 1 and wherein each intermediate thrusting device consists of cooperating cam shoulders on the two members affording a wedging action, and these are designed to cause a quick closing followed by a powerful grip upon the bolt.
- 10 5. A wrench as in claim 1 and wherein the longitudinal slots in the first handle and slide members are oppositely inclined thereby to give a transverse movement to the pivot pin during closing and thus modify the action of the second intermediate thrusting device.
- 15 6. A bolt wrench having a first handle member carrying an outer jaw and a slide member slidable endwise on the first handle member and carrying an inner jaw and a second handle member swing-

able relatively to the first to close and open the wrench; and characterized as follows: one of said three members carrying rigidly a pivot pin engaging longitudinal slots in the other two members thereby connecting the three members while permitting longitudinal movements of each relatively to the others and swinging of the second handle member, the two handle members having between them an intermediate device causing outward endwise thrust of the second handle member accompanying its swinging approach to the first, and the second handle member and slide having between them an intermediate device causing outward thrust of the slide accompanying the swinging approach of the second handle member, whereby swingingly closing the two handle members causes the jaws to close upon the bolt head or nut.
